WIRE-BENDING TOOL

William R. Brewer, Beaver Falls, Pa., assignor to Armstrong Cork Company, Lancaster, Pa., a corporation of Pennsylvania

Filed June 21, 1963, Ser. No. 289,523

3 Claims. (Cl. 72—388)

This invention relates to a hand tool for gauging the location of and making bends in wire, which tool is adapted to be held and operated by one hand and comprises a pair of spaced-apart pivoted members having wire-holding and wire-bending elements, adapted to be brought into operative relationship to perform their intended function by a single action consisting of pressing the handle portions of the pivoted members toward each other.

The tool of this invention is particularly adapted to be used in gauging the location of the bend and bending of wires used in the suspension of certain types of acoustical ceiling. It is common practice to suspend such acoustical or decorative ceilings beneath the existing structural ceiling or roof support. In the installation of these ceiling suspension systems, a plurality of wires are attached to an existing ceiling structure or roof support and allowed to hang freely at predetermined spaced intervals. A reticulated grid system comprising main runners and cross runners is attached to the free ends of these suspended wires. Openings are provided in the runners to receive the free ends of the wires. In order to pass the wires through the openings it is necessary to bend the wires at 90° angles at definite points so that the reticulated grid system will be suspended in a level arrangement regardless of irregularities in the structural ceiling or roof structure.

Prior to this invention it was customary practice to bend the wire by grasping it between the thumb and forefinger at the point judged to be the place where the bend should be made. Then, lineman's-type pliers were positioned to this point by the free hand and by a holding and twisting motion of the hand holding the pliers, the wire was bent at a 90° angle. One of the primary objects of the present invention is the provision of a wire-bending hand tool which will enable the user to uniformly reproduce L-shaped bends on a wire with a single movement of one hand.

Another object resides in the provision of a wire-bending hand tool including an adjustable gauge means to determine the exact point where the wire should be bent in relation to the parts with which the wire is to be ultimately used.

A further object is the provision of a wire-gauging and bending hand tool which is simple in construction, easily employed, and economical to produce.

The above and other objects will appear more clearly from the following detailed description when taken in connection with accompanying drawings which illustrate a preferred embodiment of the invention.

In the drawings:

FIGURE 1 is an isometric view showing the tool of this invention in its open position with a wire in position to be bent shown in dotted lines;

FIGURE 2 is an isometric view showing the tool of this invention in its gauging position on a main runner prior to bending of the wire;

FIGURE 3 is an isometric view showing the tool of this invention in its closed position with the bent wire shown therein in dotted lines, and

FIGURE 4 is a top plan view of the tool with the handles broken away showing the wire as it is positioned in the tool after being bent.

As shown in the drawings, the improved wire-bending

and gauge tool comprises pivoted members 1 and 2 having head portions 3 and 4 and handle grip receiving extensions 5 and 6 to which handle grips 7 and 8 are attached by means of rivets 9 and 9'. Members 1 and 2 are adapted to rotate around pivot stud 10 upon which head portions 3 and 4 are mounted and held in spaced relationship along the axis of the pivot stud 10 by a spacer 11. A gauge plate 12 is provided on head portion 3 of member 1 by means of screws 13. (See FIGURE 2.) Fitted in the recessed portion 14 of gauge plate 12 by means of screws 15 is a spacer 16. Carried in gauge plate 12 is a wire-receiving slot 17 positioned in alignment with a similar slot 18 in head portion 3 of member 1. Head portion 4 of member 2 is formed with a wire-bending surface 19 and a cut-back portion 20 which is adapted to rest against stop pin 21 projecting from the lower left part of head portion 3 when the tool is held in open position by means of spring 22. When the tool is in its open position, as shown in FIGURES 1 and 2, wire-bending surface 19 is positioned to the rear of slot 18 in head portion 3 of member 1. The spacer 16, of course, may be varied in thickness or be adjustably affixed to gauge plate 12 in a known manner to increase or decrease the depth of the bend made on the wire with relation to the top of a main runner.

The manner in which the tool of this invention is used is shown in FIGURES 2 and 3. As shown in FIGURE 2, the recessed portion 14 carrying spacer 16 is placed on the main runner 23 as shown. The wire 24 is then positioned in wire-receiving slots 17 and 18 of gauge plate 12 and head portion 3 of pivoted member 1. The hand holding the tool will then depress the handles 7 and 8. This will start the bend in the wire 24 by rotating the head portion 4 of pivoted member 2 around pivot stud 10, bringing wire-bending portion 19 of head 4 into contact with wire 24 while it is held in wire-receiving slots 17 and 18. The bend would be completed by moving wire 24 slightly away from runner 23 and continuing to depress the handles of the tool. The position of the parts of the tool and the bent wire at the completion of the bend is as shown in FIGURES 3 and 4. As best seen in FIGURE 4, a spacer 11 is provided between head portions 3 and 4 to allow room for a section of the bent portion 26 of the wire 24. Upon release of pressure on handle 6 and 7, pivoted member 2 is rotated around pivot stud 10 by means of outward pressure of spring 22 until cut-back portion 20 on the head 4 comes to rest against stop pin 21. The bent wire is then released from the tool and is inserted into hole 25 in runner 23, bent upwardly and wound around itself.

I claim:

1. A wire-bending and gauging tool comprising a pair of pivoted levers, each lever comprising a handle portion and a head portion mounted in spaced relationship along the axis of a transverse pivot stud, spacing means on said stud between said levers, a gauge plate having a wire-receiving slot across the width of the top edge thereof, said gauge plate being positioned on the outer surface of the head of the first of said levers, said first lever having a wire-receiving slot positioned in alignment with the slot in said gauge plate, an extended portion on said gauge plate projecting out beyond the end of said first lever head and provided with a recessed portion on the inner face thereof adjacent its outer end and a spacer plate positioned therein, the second lever having a wire-bending surface on the upper portion of the head thereof, said wire-bending surface being positioned rearwardly out of alignment with said wire-receiving slots when the tool is in its open position, a recessed notch on the lower portion of said second lever head and a stop pin projecting from the inner face of said

first lever head and adapted to butt against said notched portion of said second lever to limit the travel thereof, spring means being provided between the handle portions of said levers to hold the tool normally in its open position.

2. A wire-bending hand tool including a point-of-bend locating gauge comprising two pivoted lever-type members mounted on a transverse pivot stud, spacing means positioned on said stud between said lever-type members, a gauge plate attached to the outer surface of and extending out beyond the head portion of one of said lever-type members, a recessed area on the inner face of the extending portion of said gauge plate, said area being recessed in an amount calculated to properly position the bending elements of the tool when in use, said gauge plate being provided with a wire-receiving slot across the width of the top edge thereof in alignment with a similar slot in said attached pivoted member, a wire-bending surface on the other pivoted member adapted to be moved past said slots in the gauge plate and attached pivoted member to bend a piece of wire when positioned therein.

3. In a wire-bending and gauging hand tool comprising a pair of pivoted lever-type members, each member having a handle portion and a head portion mounted in spaced relationship on a transverse pivot stud, the improvement comprising a substantially rectangular wire holding and positioning depth-of-bend gauge plate removably attached to the outer surface of the head portion of one of said pivoted lever-type members, said gauge plate having a portion thereof extending beyond the head portion of said attached lever-type member in a

direction parallel to the length of the tool and at right angles to the length of a wire to be bent when held by said tool, said extending portion of said gauge plate having a rectangular recessed area extending completely across the inner face thereof adjacent its outer end, said rectangular recessed area having top and back wall portions disposed at right angles to each other and adapted to be placed in contact with an object to which a wire is to be attached, to simultaneously steady the tool, properly space the wire horizontally away from the object and position the tool to assure proper vertical location of a bend to be made in the wire with respect to an opening in the object through which the bent portion of the wire must pass, said gauge plate and said head portion of said attached pivoted lever-type member having a continuous slot across the width of the upper edges thereof, said slot adapted to hold a wire to be bent by a wire-bending surface on the other pivoted member when said wire bending surface is moved into operative relationship therewith by pressing the handle portions of said lever-type members toward each other.
